UNITED STATES PATENT OFFICE.

MARTIN O. REHFUSS, OF PHILADELPHIA, PENNSYLVANIA, ASSIGNOR TO UNITED STATES CHAIN AND FORGING COMPANY, OF PITTSBURGH, PENNSYLVANIA, A CORPORATION OF PENNSYLVANIA.

MACHINE FOR MAKING LINKS FOR CHAINS.

1,360,021.

Specification of Letters Patent. Patented Nov. 23, 1920.

Application filed March 14, 1919. Serial No. 282,704.

To all whom it may concern:

Be it known that I, MARTIN O. REHFUSS, a citizen of the United States, residing in Philadelphia, Pennsylvania, have invented 5 Machines for Making Links for Chains, of which the following is a specification.

One object of this invention is to provide a relatively simple, substantial and compact machine for forming a predetermined length 10 of rod or wire material into a chain link and which shall be characterized by the inclusion 15 of a single reciprocating slide, together with coacting elements whereby the link is completely formed by a single movement of said 20 slide in one direction;—the invention contemplating a novel arrangement of bending arms and forming rolls relative to a king post on which the link is to be formed.

These objects and other advantageous ends 25 I attain as hereinafter set forth, reference being had to the accompanying drawings, in which,

Figures 1 and 2 are respectively a side elevation and a plan of a machine constructed 30 in accordance with my invention;

Fig. 3 is a front elevation of the machine shown in Figs. 1 and 2; and

Figs. 4 and 5 are plan views like Fig. 2, showing the king post in horizontal section 35 and illustrating the operation of the machine.

In the above drawings 1 represents a flat top base plate on which are fixed integrally or otherwise a pair of longitudinally extending 40 parallel ribs 2. Each of these has fixed 35 to a portion of its top face an overhanging plate 3 co-acting with it to form a guideway for a block or slide 4 operative upon the top face of the base 1 on which it is reciprocable by any suitable mechanism whose detail construction forms no part of the present invention.

On the forward end of each of the parallel ribs 2 is mounted a roller 5 rotatable upon 45 a vertical spindle 6 whose lower end is threaded into or otherwise fixed in said rib and whose upper end is supported by an overhanging bracket 7 carried by the base plate 1. Adjacent one end of the latter is a 50 vertically movable head 8 slidably guided in a standard 9 (Fig. 1) supported in any suitable manner so that the block or slide 4 is movable under its lower end. Said lower

end has two differently shaped portions 10 and 11 of which the first has the outline of 55 the space within a partially formed link and the latter has the outline which it is desired to give to the interior of the finished link.

In order to hold a rod α against the king post, I provide a bar 12 slidable longitudinally of the block 4 in a guideway 13 mounted thereon, and cylindrically concave its forward end to fit the cylindrical surface of said rod of which the link is to be formed. Upon the upper face of the slide or block 4 60 on either side of the bar 12 I pivotally mount a swinging arm 14 upon a bolt 15 and so arrange said arms that they extend forwardly of the block from said pivot bolts and are free to swing toward and from each 65 other.

For forcibly moving said arms toward each other I form them with or otherwise attach to them adjacent the outer sides of 70 their free ends, cam structures 16 positioned 75 to coact with the rollers 5 as the block or slide is moved forwardly. Said arms also carry on their adjacent sides oppositely placed grooved bending rolls 17 so formed as to engage the end portions of a rod α held 80 against the king post, and the cam surfaces 16 are so mounted that when they are acted upon by the rolls 5 as the slide 4 is moved forward they cause the rolls 17 to coact with the king post to bend said rod α into its 85 intermediate form indicated at α^1 in Fig. 4.

Also mounted on opposite sides of the holding bar 12 is a second pair of peripherally grooved bending rolls 18 rotatably mounted on spindles 19 projecting vertically up from the slide 4 and so positioned as to coöperate with the part 11 of the king post to give the partially formed link α its 90 final shape α^2 , and the arms 14 are so bent or curved as to permit them to fulfil their functions without interference with these latter rolls. It is noted that the guide ribs 3 are 95 so formed as to serve as stops to limit the outward swing of the arms 14 and to some extent support them at the time of their first 100 engagement with the rod α to be bent.

Under conditions of operation the head 8 is lowered in its guide until the larger portion 10 of the king post lies in a horizontal plane including the bar 12 and after a predetermined length of the rod α to be formed 105

has been fed or placed back of this part of said post, the holding bar 12 is moved so as to firmly clamp the middle portion of the rod against it. Thereafter the slide or block 4 is moved forward toward and under the king post, thus causing the grooved rolls 17 to engage the ends of said rod x and bend these at first forwardly, then as the cam surfaces 16 coat with the rollers 5, force them first parallel with each other around the part 10 of the king post and finally curve them in toward each other into the relative positions indicated at x^1 in Fig. 4.

As the forward movement of the slide 4 is continued the cam portions 16 of the arms 14 pass the rollers 5 and the head 8 is raised so that the small portion 11 of the king post is brought into the hollow of the partially formed link, the gripping action of the holding bar 12 being temporarily relaxed during this upward movement and thereafter again applied. The rolls 18 now come into engagement with the opposite end portions of the partially formed link x^1 , forcing its extremities toward and finally into intimate engagement with each other so that it assumes the form x^2 desired in the finished link. The slidable clamping rod 12 is then retracted, the king post is raised and the finished link removed, these operations being performed either before or after the slide 4 has been moved rearwardly to its original position shown in Fig. 2. Thereafter the king post is again lowered until its portion 10 is immediately adjacent the end of the clamping bar 12, after which another length x of rod material is placed in position and gripped to the post by said bar as before, prior to the formation of a second link.

From the above description it will be seen that by the mechanism illustrated I first give a straight length of rod material a preliminary bend to form a partially closed link and thereafter complete the bending to cause said intermediate shape to assume the form of a finished link. While these operations occur successively, they are both performed during a single forward movement of the single slide 4 and result in the formation of a link of the desired form whose extremities are in engagement and are not deformed in any way by the forming operation.

I claim:

1. The combination in a link forming machine of a reciprocating slide; a king post; and mechanism on said slide for bending a straight rod around the post to form a complete link during movement of said slide in one direction.
2. The combination in a link forming machine of a reciprocating slide; a king post having two differently shaped link forming parts; and mechanism on said slide for bending a straight rod around the two parts of the post successively to form a complete link

during movement of said slide in one direction.

3. The combination of a reciprocating slide; a king post; and two pairs of bending members on the slide placed to successively engage a length of rod material to bend it around the post in the form of a complete link during the movement of said slide in one direction.

4. The combination in a link forming machine of a reciprocating slide; a king post; two pairs of bending rolls on the slide mounted to successively engage a rod held against the king post; and means for supporting one pair of said rolls to permit it to be bodily moved toward the king post during its operation on the rod under treatment.

5. The combination in a link forming machine of a reciprocating slide; a king post; two arms pivotally mounted on the slide; members carried by said arms for engaging a rod to be bent around the king post; means for swinging the arms toward each other while they are acting on the rod; and members also carried by the slide for completing the formation of the link partially shaped by said swinging arms, during a movement of said slide in one direction.

6. The combination in a link forming machine of a reciprocable slide; a king post; a pair of rollers for operating on a rod held against the king post; means for causing bodily movement toward each other of said rolls during their operation on the rod; and a second set of rolls mounted on the slide in positions to complete the formation of a link partially formed by said first rolls, during movement of the slide in one direction.

7. The combination in a link forming machine of a reciprocating slide; two arms pivoted thereon; a king post; rolls carried by said arms; a cam mechanism for forcing the arms with the rolls toward each other as the slide is moved in one direction to cause said rolls to give preliminary bends to a rod engaged by the post; with a second pair of relatively fixed rolls positioned on the slide to engage the partially formed link primarily shaped by said first rolls, to complete the link.

8. The combination in a link forming machine of a king post having a plurality of link shaping portions; a reciprocating slide; a device on said slide for giving a straight rod a preliminary shape when it engages one of the parts of the king post; and a second device also carried by the slide for giving the partially formed link a final shape upon the second part of the king post.

9. The combination in a link forming machine of a longitudinally adjustable king post having two link forming portions; a reciprocating slide; and two sets of rollers mounted on the slide to successively engage a length of rod material and respectively

give it a preliminary form on one part of the king post and thereafter give it a final form on the second part of said post, while said slide is being moved in one direction.

5 10. The combination in a link forming machine of a king post; a reciprocatory slide; means for clamping a length of rod material successively to two differently shaped portions of said king post; and two sets of members carried by the slide for operating on said rod material first when it is engaged with one part of the king post and thereafter when it is engaged with the second part of said post and during a single movement of the slide in one direction.

15 11. The combination in a link forming machine of a supporting structure having abutments; a slide reciprocable on said base structure; two members pivoted on the slide and each including a cam portion placed to coact with one of the abutments as the slide is moved in one direction; rolls carried by said members respectively; a king post; and two other rolls relatively fixed on the slide

for engaging a length of rod material to complete a link after said material has been given a preliminary form by said first rolls.

12. The combination in a link forming machine of a slide; a king post; a pair of rolls movably mounted on the slide; means for causing said rolls to pass around from one side to the other of the king post as the slide is moved in one direction to give a length of rod material a preliminary form; and members also on the slide for subsequently engaging the partially shaped link to force its ends into substantial engagement and complete the link.

13. The combination in a link forming machine of a reciprocating slide; a king post; and two independent sets of devices on said slide positioned to successively bend a straight rod around the post to form a complete link during movement of said slide in one direction.

45 In witness whereof I affix my signature.

MARTIN O. REHFUSS.
